[57] **CLAIM**

The ornamental design for a tool tray, substantially as shown and described.

DESCRIPTION

FIG. 1 is a top plan view of a tool tray showing our new design;

FIG. 2 is a front elevational view thereof;

FIG. 3 is a side elevational view thereof, the opposite side being a mirror image thereof;

FIG. 4 is a rear elevational view thereof;

FIG. 5 is a bottom plan view thereof;

FIG. 6 is a cross-sectional view thereof taken along lines 6—6 of FIG. 1.

FIG. 3

FIG. 4

FIG. 6

FIG. 5
